Inventor

UNITED STATES PATENT OFFICE

HARRY H. BOILES, OF JERSEY CITY, NEW JERSEY

DISPENSING DEVICE

Application filed November 3, 1926. Serial No. 145,987.

This invention relates generally to shaving brushes, particularly to fountain or reservoir brushes which involve means wherein certain operations thereof cause soap, either 5 in liquid or paste form, to be discharged into the bristles of the brush.

The primary object of the invention is to provide a brush of such construction that the operation thereof will be extremely simple, and which is equipped with improved means for preventing accidental discharge of soap into the bristles.

A further object of the invention is to provide in a brush of that type wherein a sliding piston is employed for causing the discharge of soap into the brush, improved piston means so constructed as to prevent air gaining access to the soap reservoir; means to prevent soap interfering with free action 15 of the piston, and means to hold the piston against becoming detached from its operating device.

A further object is to provide a brush of the character briefly stated of that type 20 wherein a piston or plunger is employed for causing the soap to be discharged into the brush, and which is featured with means for preventing rotation of the plunger.

A still further object resides in an improved brush head construction which greatly facilitates recharging the same with paste or liquid from the ordinary well-known collapsible tube container.

Still further and particular objects reside 35 in the construction of a pressure operated brush head which is of extremely simple construction, which is composed of but few readily assembled parts, which has these parts so arranged and assembled as to minimize the opportunity for wear, breakage or derangement, which is capable of operation in such manner as to minutely control the quantity of soap discharged into the bristles, which may be readily taken apart for cleaning or soap replenishing operations, and which will prove highly practical and efficient 40 in use.

With these objects in view, together with others which will appear as the description 45 proceeds, the invention consists in the novel

construction, combination and arrangement of parts, all as will be described more fully hereinafter, illustrated in the drawings and particularly pointed out in the claims.

In the drawings:—

Fig. 1 is a side elevation of a shaving brush embodying the invention,

Fig. 2 is a view showing the brush taken apart and in the process of refilling or in operation with a well-known type of shaving soap container,

Fig. 3 is a sectional view taken longitudinally through the brush head and illustrating the device ready for use,

Fig. 4 is a transverse sectional view taken substantially upon line 4—4 of Fig. 3, and

Fig. 5 is a similar view taken upon line 5—5 of Fig. 3.

The brush of the present invention comprehends a head composed of separable parts, one of which contains a reservoir for the reception of shaving soap or paste and from which the paste is to be discharged into the brush bristles. The other part carries with it the pressure operated means for forcing the soap from the reservoir. These parts may be readily separated, when desired, for cleaning or replenishing purposes, and are so constructed as to render it impossible to improperly readjust these parts with respect to each other. Associated with one of these parts is a safety device which normally operates to prevent discharge of the paste or soap, whereby to obviate the possibility of leakage or untimely discharge of the soap or paste.

The invention comprehends, furthermore, an improved construction of head which permits of ready application thereto of the threaded end of the familiar collapsible paste tube. While this structure permits of the ready filling of the reservoir, it also permits of the head being associated direct with a collapsible tube so that the latter, if desired, may be used temporarily with the head to afford a soap discharging element.

More particularly, the brush consists in a head 6 formed of any desired material and of proper size. This head is of cylindrical formation and is provided axially thereof with an annular bore 7 constituting a soap

or paste reservoir. The walls of this bore near one end are preferably tapered as represented at 8 and merge with a comparatively small opening 9 centrally and longitudinally disposed in the head and constituting a discharge opening. The walls at the opposite end of this bore are threaded as at 10, to accommodate the threads 11 upon the exterior of a discharge nozzle forming part of the well known collapsible paste tube 12. To this end, the bore of the head is of a size to properly accommodate the discharge end of the collapsible paste tube.

The brush proper is represented at 13, and the bristles thereof may be secured together at their inner ends in any preferred manner, and attached to the discharge end of the head 6. However they may be secured together, the central portion is to be so treated as to permit of the passage therethrough of paste discharged from the reservoir through the opening 9.

The discharge end of the head 9 has disposed substantially diametrically thereof a slot 14, within which a valve plate 15 operates. The plate 15 snugly fits within the said slot yet is capable of freely sliding movement therein. This plate is provided with an opening 16 corresponding in size to the discharge opening 9, so that when these openings are aligned, free passage of paste therethrough is permitted. The outer end of the plate 15 is secured to one end of a flat spring 17, the opposite end of said spring being anchored in the exterior surface of the head 6. The head 6 is recessed as at 18 to permit of movement of the spring in an inward direction, and this recess may be of substantially the same breadth as the spring 17. An operating plate or knob 19 is secured to the exterior surface of the spring 17 to facilitate the operation of the latter with the fingers or thumb. The spring is so associated with the valve plate 15 as to normally maintain the latter in closing position, that is, the opening 16 is brought into alignment with the discharge opening 9 of the reservoir. It will be understood, of course, that immediately upon release of the spring 17, the latter will assume normal position, closing the valve.

Associated with the outer end of the head 6 is a shell 20, which is preferably hollow, and is threaded internally at its inner end to threadedly engage with the exterior of the head 6. This threaded engagement of these two elements of the brush handle permits of the parts being readily detached from each other when desired. The shell 20 is provided with a diaphragm 21 near its inner end having a central opening aligned with the reservoir 7 and of substantially the same diameter as the latter. This diaphragm slidably receives a piston or plunger 22, equal in diameter to the bore of the head 6, and this piston is adapted to reciprocate within said

bore. The piston 22 is itself provided with a longitudinal internally threaded bore to receive a threaded stem or shank 23 carried by a revoluble plate or cap 24. This plate is preferably of the same diameter as the outer end of the shell 20, and is rotatably carried by the latter.

The shell 20 at its outer end is provided upon its exterior with an annular shoulder to accommodate a flange 25 projecting inwardly from the plate or cap 24, and at spaced intervals in the diameter of the shell bearings in the form of balls 26 are arranged to bear against the said flange and to reduce the friction between the same and the said shell. An annular ring 27 fits within the shoulder and behind the several balls 26, and is held to the cap by means of screws or pins 28.

The diaphragm 21 is provided with an inwardly projecting tooth 29 engaged in a slot 30 disposed longitudinally in the exterior of the piston or plunger 22, to maintain the latter against rotation and to permit of the plunger sliding longitudinally through the said diaphragm.

It will be observed that the tooth 29 projects into a recess or slot 30 closed at both ends. The closure for the slot at its outer end, designated at 31, constitutes a stop to limit the outward movement of the piston, and by engagement with the tooth 29 will prevent the piston becoming detached from the screw 23 should the latter be operated when the shell 20 is disengaged from the part 6. The closures for the slot ends may be struck up from the metal of the member 22 after assembly, or may be formed in other ways. By closing the channel or slot at the outer end of the plunger, soap is prevented gaining access to and clogging the channel. The plunger, or at least the inner or operative end thereof, fits snugly with the walls of the reservoir 7 to prevent soap working between the said walls and the plunger body. By this construction, danger of clogging of the plunger is eliminated, and, furthermore, such fitting of the parts prevents air gaining access to the reservoir, whereby drying or hardening of the soap is obviated. The tight fitting of the diaphragm or plate 21 serves in keeping air out of the reservoir. The elimination of threads from the exterior of the plunger and interior of the reservoir overcomes possibility of clogging or jamming of the plunger.

In operation, the shell is removed from the head and the externally threaded nozzle 11 of a soap or paste container is applied to the threaded end of the reservoir 7. Collapsing of the said tube will cause the contents thereof to be discharged into the reservoir, and when the latter is filled the collapsible container may be removed. The shell 20 is then applied to the head 6 by screwing, and the plunger 22 will be aligned

with the reservoir 7. To operate the brush thus charged, it is but necessary to rotate the plate or cap 24, as the screw 23 carried thereby will at once operate to drive the piston or plunger 22 into the reservoir 7. Such operation, however, will not cause discharge of any paste from the reservoir, owing to the fact that the plate 15 normally closes the discharge end of the reservoir. It is necessary, therefore, that the valve 15 be moved so that the opening thereof will be brought into alignment with the discharge end of the reservoir before the paste can be forced into the brush. This permits of the quantity of soap to be accurately governed, and precludes accidental discharge of soap which would be caused by merely rotating the plate. Furthermore, the lathering operation may be greatly facilitated, as initially the cap may be rotated with the valve closed so as to exert a high degree of pressure upon the contents of the reservoir. When it is desired then to discharge soap into the bristles, it is but necessary to slightly depress the spring 17, and immediately upon the openings becoming in registry, the soap will be forcibly ejected into the brush.

As has been heretofore stated, the head 6 may be used directly with the soap container 12, if desired, and the check valve will prevent entry of any soap to the bristles should the compressible tube be accidentally squeezed.

While the above is a description of the invention in its preferred embodiments, it is nevertheless to be understood that variations in the details of arrangement, the combination and assemblage of parts may be readily resorted to without departing from the spirit of the invention as defined in the claim.

Having thus described my invention, I claim:

A dispensing device of the class described comprising a reservoir member having a longitudinal bore, a shell detachably secured to one end of said reservoir member and having a lateral internally projecting tooth, a plunger member slidably engaging said bore and provided with a longitudinal groove cooperating with said tooth to prevent relative rotation between said plunger and member, said plunger having an internally threaded bore, a cap member rotatably mounted on the outer end of said shell, a threaded stem rigidly secured to said cap and threaded in said plunger bore whereby when said cap member is rotated relative to said shell, said plunger will be advanced or retracted in said reservoir member, substantially as described.

In testimony whereof I affix my signature.
HARRY H. BOILES.
